Inventors:

Prescott & Judson, by their

Attorney G.B. Jones

United States Patent Office.

WILLIAM H. PRESCOTT AND WHITCOMB JUDSON, OF GALESBURG, ILLINOIS.

Letters Patent No. 75,789, dated March 24, 1868; antedated March 9, 1868.

ODOMETERS.

The Schedule referred to in these Letters Patent and making part of the same.

TO ALL WHOM IT MAY CONCERN:

Be it known that we, WILLIAM H. PRESCOTT and WHITCOMB JUDSON, of Galesburg, in the county of Knox, and State of Illinois, have invented a new and useful Improvement in Odometers; and we do declare that the following is a full, clear, and exact description of the construction and operation of the same, reference being had to the accompanying drawings, making a part of this specification, in which—

Figure 1 is a top view.

Figure 2 is a view showing points on end of driving-shaft, and the side of case enclosing the odometer.

Figure 3 is a top view, with casing and dial-plate removed.

Figure 4 is a view of the under side of dial-plate.

Figure 5 is a view of under side of ratchet-wheel.

Figure 6 is a section of the odometer, as indicated by line *v w* of fig. 3, showing end of eccentric-shaft and the slide.

Figure 7 is a transverse central section of the odometer, as indicated by line *x y* in figs. 1, 3, and 4.

Like letters in the different figures of the drawings indicate like parts.

The nature of our invention consists, first, in providing a stationary dial-plate with two sets of figures, and two hands operated by suitable gearing, connected therewith, so that one hand, called a mile-hand, indicates each mile from one to fifty, and the other hand acts as a multiplier, moving one space at the end of each fifty (50) miles travelled, thus indicating the distances over fifty to five hundred (500) or more miles; second, in providing an eccentric-wheel or pin upon the end of the actuating-shaft, which operates in an oblong slotted slide, with a pawl, by means of which the required motion is given the hands.

To enable others skilled in the art to make and use our invention, we will proceed to describe its construction and operation.

A is a stationary dial-plate, properly divided, marked, and numbered, with two sets of figures, (see fig. 1;) one for the mile-hand *a*, which indicates each mile, from one to fifty, and the other for the multiplier-hand *b*, which counts by fifties, from one to five hundred, or more, miles. We construct a stationary wheel, *c*, attached to upright shaft *B*, with fifty-one cogs or teeth, and a movable wheel, *d*, with fifty cogs or teeth, having square hub, *e*, which works over the round shaft *B*. The under face of wheel *d* works upon the upper side or face of the stationary wheel *c*, as seen in fig. 7, so that the teeth or cogs of the pinion *f* work in both those wheels.

C is a ratchet-wheel of such size and number of teeth, and the gearing connected with it so arranged as that it makes one revolution during each mile travelled by the carriage to which the odometer is attached. A pinion, *f*, is properly arranged and attached to the lower side of the ratchet-wheel *C*, so that the teeth engage properly with the teeth of wheels *c* and *d*, (see fig. 5.)

D is a loose hub, fitted upon the square hub *e*, and provided with a tooth, *g*, for the purpose of operating the ratchet-wheel *E*, attached to under side of dial-plate, connected with hand or multiplier *b*, as seen in fig. 3.

F is an eccentric on the end of the actuating-shaft *G*, which, by means of the elongated slotted slide *H*, and pawl *I*, operates the ratchet-wheel *C*.

Operation.

The ratchet-wheel *C*, to which the pinion is attached, makes one revolution during each mile travelled, and, by means of the pinion, and the difference in the number of teeth in the wheels *c* and *d*, moves wheel *d* one notch or tooth forward, and the hand *a* indicates on the dial one mile, and so on up to fifty miles, as seen in fig. 1. And it will be seen from the description that the carriage must travel fifty miles, causing fifty revolutions of the ratchet-wheel *C*, in order to produce one entire revolution of wheel *d*, which will bring the tooth *g* in contact with ratchet-wheel *E*, and thus move the hand or multiplier *b* one space, indicating thus the fifties and hundreds of miles travelled, and adding to this the number of miles indicated by the mile-hand, gives, in miles, the exact distance travelled.

Claims.

Having thus fully described our invention, what we claim therein as new, and desire to secure by Letters Patent, is—

1. Imparting motion to the gearing by means of an eccentric on the end of the actuating-shaft, operating a slide with a pawl, substantially in the manner and for the purpose as herein described.
2. Providing a stationary dial-plate with two sets of figures and two hands, a niple-hand and a multiplier, operated substantially in the manner and for the purpose as herein described.
3. The construction of the ratchet-wheel C with pinion e, the stationary and movable wheels c and d, the loose hub D, with tooth g and ratchet-wheel E, as arranged and operated, substantially in the manner and for the purposes as herein described.

W. H. PRESCOTT,
WHITCOMB JUDSON.
